UNITED STATES PATENT OFFICE

150,715

DESIGN FOR A MORTAR AND CEMENT FINISHING TOOL

Theodore T. King, Grand Prairie, Tex., assignor
of forty-nine per cent to J. C. Young, Grand
Prairie, Tex.

Application March 12, 1947, Serial No. 137,561

Term of patent 14 years

(Cl. D93—4)

To all whom it may concern:

Be it known that I, Theodore T. King, a citizen
of the United States, residing at Grand Prairie,
in the county of Dallas and State of Texas, have
invented a new, original, and ornamental Design
for a Mortar and Cement Finishing Tool, of which
the following is a specification, reference being
had to the accompanying drawing, forming part
thereof.

In the drawing:

Figure 1 is a view in top plan of the mortar
and cement finishing tool, showing my new
design;

Figure 2 is a side elevation thereof;
Figure 3 is a bottom plan view;

Figure 4 is a front elevation; and
Figure 5 is a rear elevation.

I claim:

The ornamental design for a mortar and cement
finishing tool, as shown.

THEODORE T. KING.
